UNITED STATES PATENT OFFICE.

EARL W. KOPPE, OF KINGMAN, ARIZONA.

LATHE ATTACHMENT FOR GRINDING CYLINDERS.

1,361,736.

Specification of Letters Patent.

Patented Dec. 7, 1920.

Application filed April 14, 1919. Serial No. 289,831.

To all whom it may concern:

Be it known that I, EARL W. KOPPE, a citizen of the United States, residing at Kingman, in the county of Mohave and State of Arizona, have invented certain new and useful Improvements in Lathe Attachments for Grinding Cylinders; and I do declare the following to be a full, clear, and exact description of the invention, such as will enable others skilled in the art to which it appertains to make and use the same.

This invention relates to grinding devices, and it relates more specifically to an improved lathe attachment for grinding cylinders.

The main object of this invention is to generally improve upon devices of this character by providing a construction that is comparatively simple and easy to manufacture, attach and operate, and which is very efficient, strong and durable.

Other objects and advantages may become apparent to persons who read the following details of description in connection with the accompanying drawings in which,

Figure 1 is a view partly in side elevation and partly in vertical section, illustrating my improved lathe attachment in its operative position on a lathe of ordinary construction.

Fig. 2 is a vertical sectional view, the section being taken along the line 2—2 of Fig. 1.

Fig. 3 is a vertical sectional view, the section being taken along the line 3—3 of Fig. 1.

Referring to these drawings in detail, in which similar reference characters correspond to similar parts throughout the several views, and in which the lathe will not be described in detail:

The invention consists broadly in the combination of my improved grinding attachment with a face plate 5 having radial slots 6 terminating adjacent to the center and circumference of the face plate. In other words, the face plate 5 is of ordinary construction so that my improved lathe attachment is attachable to most every kind of lathe which carries a face plate.

My improved attachment comprises an attaching plate 7, a mandrel 8, a tubular rotor 9, an emery wheel or other suitable grinding wheel 10, a driving belt 11, a belt tight-

ener 12, and other elements to be mentioned and described hereinafter.

The face plate 7 is preferably rectangular, as shown in Fig. 3 and the mandrel 8 has one end seated and secured in a central aperture of the attaching plate, the elements 7 and 8 being preferably united by shrinking the face plate upon the mandrel. At diametrically opposite points of the face plate, suitable apertures are provided for the reception of stud-bolts 13, the same comprising nuts 14, whereby the attaching plate may be secured in different eccentric positions on the face plate 5, it being understood that the bolts 13 extend respectively through two diametrically opposite slots 6 of the face plate.

In the extreme ends of the slots 6 in which the bolts 13 are seated, a second pair of bolts are seated, the latter being shown at 15, nuts 16 thereof being effective to secure these bolts in their respective positions. Each bolt 15 has its head bored radially therethrough and screw-threaded to receive an adjusting screw 17, these adjusting screws each having one end against the attaching plate, as illustrated in Figs. 1 and 3.

From the foregoing description and accompanying illustration, it will be seen that the screws 17 have their axes alined in the axial plane of the face plate 5, and therefore, when one of these adjusting screws is loosened, and the other is tightened, this operation effects a radial movement of the attaching plate and mandrel, provided that the nuts 16 are sufficiently loose on the bolts 15 to permit such radial movement or eccentric adjustment.

The rotor 9 may be provided with ball bearings, as indicated at 18, or with any appropriate form of bearings, so that it rotates freely around the mandrel 8 under the driving influence of the belt 11, it being understood that the belt transmits its motion to the rotor through the medium of a pulley 19 which forms an element of the rotor. It should be understood that while the rotor 9 is rotating about the mandrel 8, the latter is revolving through an orbit about the axis of the face plate 5, and therefore, the belt 11 is alternately tightened and slackened during these revolutionary movements.

The belt tightener 12 comprises an arm 20 and a pulley or idler 21, the latter being carried by the arm 20, this arm being piv-

totally mounted on a portion of the mandrel 8 between the pulley 19 and the attaching plate 7. Weights 22 may be added on a supporting rod 23 for increasing the tension of the belt 11, when necessary or desirable.

The mandrel 8 is provided with an adjusting nut 22' whereby its bearings may be adjusted, and the rotor 9 is formed with a 10 screw-threaded joint 23' which permits access to the nut 22' for adjustment. In other words, the rotor 9 includes a head 24 which is screw-threaded into the tubular main portion of the rotor, and this head is also 15 formed with a screw-threaded stud 25 on which the grinding wheel 10 is secured by means of a nut 26.

In Fig. 1 an engine cylinder is generally indicated by the number 27, one or more 20 angle irons 28 securing this cylinder on the bed of the lathe.

Although I have described this embodiment of my invention very specifically, it is not intended to limit this invention to these 25 exact details of construction and arrangement of parts, but I am entitled to make appropriate changes within the scope of the inventive idea as expressed and claimed.

What I claim as my invention is:—

A cylinder grinding attachment for a 30 lathe comprising an attaching plate, means for releasably and adjustably connecting the attaching plate with the lathe plate, a mandrel extending from the center of the attaching plate, a hollow rotor rotatably 35 mounted upon the mandrel, the rotor extending beyond the outer end of the mandrel and terminating short of the attaching plate and having a drive belt receiving head at its inner end, bearings for the rotor positioned within the same adjacent the ends of the mandrel, means carried by the mandrel for retaining the rotor in place, a head 40 removably connected with the end of the rotor, a grinding element connected with the head, 45 an arm loosely mounted upon the mandrel between the attaching plate and the inner end of the rotor and held against movement longitudinally thereon by the attaching plate and rotor, and an idler pulley rotatably connected with the free end portion of 50 said arm for engaging a belt passing about the belt receiving head of the rotor.

In testimony whereof I have hereunto set my hand.

EARL W. KOPPE.
